APPLICATOR

Huna L. Apfelbaum, Brooklyn, N. Y., assignor to
Victor Metal Products Corporation, Brooklyn,
N. Y., a corporation of New York

Application January 4, 1943, Serial No. 471,269

3 Claims. (Cl. 15—140.3)

This invention relates to applicators and particularly to those of the rod type designed to be secured to a bottle cap for applying a small quantity of a medicinal liquid such as iodine, mer-curochrome or the like contained in the bottle to a part of the body.

Such applicator rods are now made almost exclusively of glass, the rod being cemented or forced into the well provided by a tubular projection in a molded cap. Many attempts have been made to hold the rod properly and securely in the cap, but such attempts have not yet resulted in a commercially satisfactory product adapted for quantity production, principally because of the difficulties involved in adequately securing the glass rod to the cap, which is usually molded of Bakelite or other synthetic plastic.

Furthermore, the applicator could not be manipulated or used without removing the cap from the bottle. This exposed the opening in the bottle or other container and permitted an objectionable amount of evaporation of the contents, as well as permitting contamination by the entrance of foreign matter into the container, and also required the user to grasp the comparatively large and unwieldy cap when using the applicator.

The present invention therefore contemplates the provision of a combined but separable cap and applicator rod so constructed that they need not be permanently secured together, but are provided with cooperating screw threads whereby the applicator may be secured to the cap when not in use and removed therefrom for use by itself independently of the cap when desired, the rod and cap being both adapted for economical manufacture and assembly, the screw assembly being dependable and efficient and eliminating the high percentage of breakage due to the use of glass rods and the unreliable attachment thereof to the cap.

The invention further contemplates the provision of a combined but separable cap and applicator, both moldable conveniently of suitable non-brittle plastic, the plastic of the rod being different, if necessary, from that of the cap, and unaffected by the liquid with which it is used, whereby the cap and rod may be separately molded in molds suitable for each and later assembled.

The invention further contemplates the provision of a shallow cap using a minimum of now scarce material and provided with an internally threaded upstanding projection having an opening serving as a discharge passage when required

and adapted to receive a correspondingly externally threaded part of an applicator rod, a liner being interposed between abutting parts of the cap and rod to prevent leakage when the applicator is in place, said applicator normally forming a closure for the cap opening.

The various objects of the invention will be clear from the description which follows and from the drawing, in which,

Fig. 1 is a combined front view and vertical section of the invention as it appears applied to a bottle.

Fig. 2 is a similar view of the cap and applicator slightly separated as when the applicator is being removed for use.

In the practical embodiment of the invention shown by way of example, both the cap 10 and the separate applicator 11 are preferably molded of suitable plastic such as Bakelite or the like. As has been indicated, plastic different from that of the cap in its resistance to chemicals, or in color, and impervious to the particular liquid to be applied by the applicator may be used for such applicator in special cases, though ordinarily this is not necessary. Both the cap and the applicator are so shaped that they may readily be molded economically by known machinery and in suitable molds and by quantity production methods. The cap is therefore preferably made comparatively shallow, that is, only sufficient internal threads 12 are provided on the depending skirt 13 of the cap to permit it to be screwed firmly on to the bottle neck 14. The sealing liner 15 is arranged against the under face of the top wall 16 of the cap and has a central hole 17 therein for the passage of the rod portion 18 of the applicator.

Upstanding from the upper surface of the cap top 16 is the central integral tubular projection 19 internally threaded at 20 and preferably of lesser outer diameter than the inner diameter of the skirt 13. The comparatively small opening 21 in the projection 19 is normally closed by the applicator. The rod portion 18 is preferably solid and of uniform diameter, being integrally joined to the enlarged head or finger grip portion 22 of the applicator by the externally threaded connecting portion 23. The outer diameters of the head and projection 19 are preferably the same so that the head forms a continuation of the projection (Fig. 1) when the parts are assembled.

Said connecting portion is of greater diameter than the rod portion and of lesser diameter than the head to form the flat shoulder 24 at the bottom of the head and the shoulder 25 at the bottom

of the portion 23. A sealing ring washer 26 is arranged against the shoulder 24 to engage the preferably flat top surface of the cap projection 19 when the applicator is screwed into the cap, thereby preventing leakage or evaporation of the bottle contents therethrough. Similarly, the top of the liner 15 preferably engages the shoulder 25 when the parts are assembled, at least partially to close and seal the bottom part of the opening 21. Since the screw threads on the connecting portion 23 correspond with the threads 20 on the projection 19, it will be seen that the applicator may be quickly and easily secured to and removed from the cap and forms an adequate closure and seal for the cap opening 21. The opening being larger than the rod portion 18, liquid adhering to and carried by the applicator may be withdrawn from the bottle without being scraped off the rod by the cap.

It will be seen that the applicator may readily be removed for use without disturbing the cap, which when once put on, remains on the bottle. It will also be seen that if it becomes necessary to pour out some of the contents of the bottle, the small opening 21 in the cap permits such pouring without disturbing the cap. Tightening of the applicator to the cap also tends to tighten the cap on the bottle neck and to maintain the sealing effect of the cap. The applicator when removed may be manipulated easily and accurately without the difficulties presented by the weight, size and position of an unwieldy cap having the applicator fixed thereto as in present devices of this nature. There is no danger of the rod portion falling out of the cap holder therefor, or any danger of the applicator breaking. The rod portion may be molded of any suitable plastic and in any color and the assembly is adapted for manufacture in a great variety of attractive designs, colors and plastics.

While a certain specific form of the invention has been shown and described, various modifications thereof may be made without departing from the spirit of the invention.

I claim:

1. A combined container cap and applicator comprising a cap molded of plastic material and having a top and an internally threaded skirt depending from the top, a projection upstanding

from the upper surface of the top and having an internally threaded passage therethrough serving as a discharge opening when the cap is applied to a container, a liner in the cap arranged against the under face of the top, an applicator molded of plastic material and securable to and removable from the top, said applicator having a rod part adapted to pass freely through the passage of said projection, an enlarged head part on the applicator terminating in a bottom shoulder and of substantially the diameter of the projection, a ring liner arranged against shoulder and adapted to be compressed against the top surface of the projection, and an externally threaded connecting part on the applicator joining the head part and the rod part and of greater diameter than the rod part and of lesser diameter than the head part, and having a bottom shoulder adapted to contact with the cap liner when the connecting part is screwed into the projection.

2. In a combined container cap and applicator, a one piece cap having an internally threaded central passage therethrough, an elongated one piece applicator having an externally threaded part intermediate its ends normally screwed into and closing said passage and removable therefrom and having an elongated rod part of lesser diameter than the threaded part and projecting therefrom, said applicator terminating beyond the threaded part in an enlarged head having a shoulder, and a liner at said shoulder adapted to engage the cap when the applicator is screwed thereinto.

3. In a combined container cap and applicator, a cap of plastic material and having an upstanding projection provided with a central discharge opening and having a flat top, the wall surrounding said opening being internally threaded, an elongated one piece applicator of plastic material, said applicator having a head terminating in an annular flat shoulder, an externally threaded connecting part adjacent said shoulder, and a rod part of reduced diameter extending from the threaded part, and a liner at said flat shoulder adapted to engage the flat top of the projection to seal said opening when the connecting part of the applicator is screwed into the opening.

HUNA L. AFFELBAUM.
